LIGHT BAR PREVENTER IN LOOMS

John Desrosiers, Cornwall, Ontario, Canada

Application February 24, 1936, Serial No. 65,234

3 Claims. (Cl. 139—348)

My invention relates to looms such as used in textile mills and is an improvement thereon.

The main object of my invention is to provide means whereby certain defects in the product of the loom, and known in the trade as light bars, may be quickly and efficiently detected and the loom automatically stopped, thereby avoiding waste of time and material.

Another object is to provide such means workable in combination with the mechanism of the loom intended to stop the same when a break occurs in the warp, known as the drop-wire mechanism, thereby removing the necessity of separate knock-off mechanism for the detector. This will remove the necessity of additional parts to the already intricate mechanism of the loom.

Other objects reside in the construction of a detector capable of being easily dismantled, and having flexibility, so as to avoid damage when accidentally coming in contact with any moving part of the loom.

Further objects will appear in the description of the preferred embodiment of my invention as shown in the drawings appended hereto.

As already mentioned, my invention is principally for the purpose of detecting light bars, understood to anyone in the trade to mean the unprovided for space between threads lying crosswise of the fabric due to many reasons, such as, failure on the part of the shuttles, improper functioning of the lay.

For some years looms have been provided with means to detect broken threads in the warp and to stop the loom immediately on the detection.

This means comprises a series of oscillating bars positioned under the warp and straddled by drop-wires supported by warp threads, there being one drop-wire for each thread arranged in such a manner that, in the event of a thread breaking, its respective drop-wire will fall and clamp one of the oscillating bars so as to prevent its movement, thereby knocking-off a clutch in the driving mechanism.

In my device, I provide a weight held by an arm or beam over the fabric at a point near the lay or rather the reed thereof on its inner stroke. The weight or head, as it may rightfully be called, rests on the fabric through the intermediary of a stylus varying in size according to the mesh produced by the loom, but large enough to be carried thereby unless the stylus meets a light bar when it will drop through. A small plunger in the head will be lifted in the latter's fall by contact with the fabric and will release a lead connecting with a modified drop-wire which will

thereby fall and clamp one of the oscillating bars and operate the conventional knock-off mechanism so as to immediately arrest the motion of the loom.

Of course, were a loom not equipped with the drop-wire knock-off system or, if desired, in any case my device may operate a separate knock-off mechanism or operate both, or again any auxiliary means of arresting further operation of the loom after a light bar has been detected.

In the drawings,

Figure 1 is a top plan view of the complete detector constructed in accordance with my invention as installed on the breast beam of a loom and as lying over a strip of the fabric, as shown;

Figure 2 is an enlarged view of the head thereof with portion cut away to show its internal parts in released aspect;

Figure 3 is an enlarged longitudinal section of the head;

Figure 4 is a side view of the device showing its relative position with the fabric, warp and loom;

Figure 5 is a view showing a drop-wire in combination with part of the conventional drop-wire component of a loom in its inoperative position;

Figure 6 is a corresponding view to Figure 5, showing the modified drop-wire in operative position;

Figure 7 is an enlarged sectional elevation of the upper part of the modified drop-wire, showing the adjustment means thereof;

Figure 8 is a top view of part of the device showing the emergency articulation of its mounting;

Figure 9 is an end view of the device as seen from the front of the loom;

Figure 10 is a top view of the device showing parts as they appear in released position;

Figure 11 is an enlarged fragmentary view of two parts of the device showing their separable articulation;

Figure 12 is an enlarged underside view of the hinge part of the device showing the detail thereof;

Figure 13 is a sectional view taken on line 13—13 of Figure 1, showing fragments of several parts pivoted together.

Similar symbols of reference denote identical parts in all the figures.

Referring to Figures 1 and 4, 15 denotes a portion of the breast beam of a loom; in the present case, the right-hand side thereof, over which passes the finished product, part of which is denoted by 16, having its selvedge 17 where shown.

The forward position of the reed of the lay is

indicated by double dotted lines 18 and part of the warp by 19. The above parts or portions of parts are, of course, merely shown as an aid in illustrating my device in order to show its approximate position on the loom and, as such, are not shown or explained in detail.

On breast beam 15, or any suitable loom member as the individual looms may govern, is fastened a slide base 20 by means of bolts or screws 21, one being at each end thereof. Slidably mounted thereover, but adapted to be set in position by means of a bolt 22 passing between it and base 20, is a foot 23, having an extension 24 provided with a vertical post 25. Resting on the extension and pivotally mounted around the post 25, by means of its sleeve 26, is an arm 27 normally lying in the same direction as extension 24. Arm 27 is held in its normal position by means of a spring 28 shaped as shown coiled around a pindle 29 on foot 23, one end resting against a pin 30, also on foot 23. The other end of the spring rests in a small saddle 31 extending downwardly from the arm 27, which it tends to press against the side of extension 24. Mounted at the end of arm 27, at right angle thereto and pointing towards the rear of the loom, is a hinge member 32 in which is pivoted one end of a beam 33, so that the latter may be free to function vertically. The other end of the beam terminates in an integral head 34 provided with a cap piece 35 held to the head by means of a screw 36 passing through the former and threaded in the latter as shown in Figures 2 and 3. Towards the extreme end of the head, a stylus 37 is mounted in a perforation which is enlarged at the upper edge thereof in order to receive the enlarged portion 38 of the stylus.

This construction is intended to prevent the stylus from falling off and to allow the same to be removable. It is held in place by the cap 35. It will be seen that the stylus is set at an angle so that its lower end will be substantially in a perpendicular plane with the end of the head. Substantially central of the head is a vertical bore 39 in which is mounted a plunger 40 provided with an integral top piece 41 extending towards the rear of the head where it is provided with a downward pin 42. Plunger 40 and pin 42 are loosely fitted in their respective bores so that they fall by their own weight until their joining piece 41 rests on top of head 42. In this position it will be seen that the plunger extends below the head, though for a shorter distance than does the stylus. In the same position, the angular portion of pin 42 crosses a horizontal slit 43 substantially in line with the top of the beam. Beam 33 is made in two parts, one lying over the other and held together by bolts 44 fastened through slits in each part so that the beam may be lengthened or shortened as desired.

Lying over beam 33 are two thin strap-like members 45 and 46, having a longitudinal slit for the best part of their length. Members 45 and 46 overlap each other and are joined together by means of a bolt 47 forming an adjustable link 48.

The rear end of link 48 is adapted to enter slit 43 in the head and is guided therein by means of a small post 49 mounted on beam 33. The other end of the link is provided with a post 50 adapted to engage the arcuate slit 51 in sector 52 of a lever 53. It will be seen in Figure 3 that, when link 48 is inserted fully in slit 43, it becomes engaged by pin 42 as the latter drops in the link and that, when it is free as in

Figure 2, the link's travel is limited by post 49.

Lever 53 is provided with a vertical sleeve 54 adapted to surround sleeve 26 of arm 27 and is thereby fulcrumed at that point. This constructional detail is clearly shown in Figure 13. 5

It has been previously mentioned that beam 33 is hinged to a piece or member 32 mounted on arm 27, but, although normally at right angle, the mounting means are yieldable. The hinged piece is provided with bars denoted by 10 numerals 55 in Figure 12 fastened to its underside. These bars are semi-cylindrical and engage with corresponding grooves in arm 27. The hinged piece is held firm to the arm by means of a bolt 56 having a square opening in the 15 hinged piece, as shown in Figure 12, so as to prevent any rotation therebetween. The lower end of the bolt passes through an opening in arm 27 and is provided with vertically-disposed lugs 57 which lie on the underside face of the 20 arm when the beam is at a right angle thereto. However, when the beam is in straight line with the arm, the lugs register with two notches 58. The bolt is held by nut 59 pressing on a spring 25 60 which, in turn, rests on the arm.

With this construction it will be seen that the beam may be shifted either one way or the other from its normal position, since link 48 is free to ride at its inner end in sector 52; the resistance against the free shifting of the beam 30 depends on the amount of pressure exerted by spring 60 adjustable by nut 59. It is evident that the beam and head may be readily removed from its support without disturbing the support nor its adjustment, by simply moving the beam 35 until the link is disengaged with sector 52 and then until the bolt frees itself through notches 58. The manner of assembly of the beam with its support is self-evident. The function of sector 52 in relation to post 50 is also evident in 40 Figure 8.

This construction permits the detector to assume the aspect shown in Figure 8 in that the head and beam may be withdrawn or forced back from their normal position without disturbing 45 the angle with respect to the fabric and yet will return to its normal position when released, due to the action of spring 28.

Referring to Figure 5, numerals 61 denote frame bars of a loom separating banks of drop-wires, one of which is denoted by 62, and over which pass warp threads from warp roller 63. One thread 64 is shown supporting drop-wire 62 by passing through its eye 65 and resting over frame bar 66. From that point the thread proceeds to the healds and reed (not shown) until it reaches the position as shown at 19 in Figure 1.

Numerals 67 denote the oscillating bars which normally are in motion when the loom is in 60 operation, but which operate a knock-off mechanism to stop the operation of the loom when their motion is arrested. When a thread breaks its drop-wire falls down, the narrow portion 68 of which straddles its respective bar 67, obviously stopping the loom. By means of a wire or thread 69, as desired, leading from a small hook 70 fastened to the end of lever 53, leading to the rear of the loom and passing over a small grooved pulley 71, a modified drop-wire 72 is 70 supported in the same relative position with respect to the oscillating bars as are the conventional drop-wires. Drop-wire 72, however, is of greater weight than warp drop-wires and is of the open form type, so that it may easily be re- 75

moved from bar 67, which it straddles, in order to prevent any interference therewith when the loom is being threaded or attended to.

Guiding pulley 71 is mounted on a bracket 73 which is in two parts, so as to be adjustable vertically as shown, its lower part being adapted to surround frame bars 66 where it is fixed by a set-screw 74. Bracket 73 is positioned outside the warp so as not to interfere with same, and for the same reason to support drop-wire 72 beyond the regular drop-wires, in the present case on the right-hand side thereof. Pulley 71 is adjustable longitudinally of the loom so that drop-wire 72 may be guided in its exact required position with respect to bar 67.

Wire or thread 69 passes through the reed on its way to support 73 and any undue play thereof is taken up by means shown in Figure 7. This means consists of a small shaft 75 mounted in the top of drop-wire 72 crossing an opening 76. It is provided with a small hole so that the thread or wire 69, after passing in small bore 77, may be tied to same. Shaft 75 is provided with a knob 78 so that, by turning the same, thread 69 may be either coiled on or uncoiled from the shaft for adjustment. The shaft is held in fixed position by the pressure of spring 79, pressing on knob 78 as shown. It will be noted that drop-wire 72 has a narrowed portion 80 corresponding to that in drop-wires 62.

In use the detector is mounted, as described, on the loom and a thread or wire, denoted by numeral 69, is tied between hook 70 on the detector lever and, after passing through reed and over pulley 71, is tied to shaft 75 of the modified drop-wire 72.

Thread 69 should be of a length which will hold its drop-wire approximately at the same level as other drop-wires on the loom. Proceeding with link 48, engaged as in Figure 3 by pin 42, which is the result of pushing the link against the angular end of the pin, whereby it will be lifted and allowed to fall in the link, the exact required height of drop-wire 72 is obtained by manipulation of its knob 78. Assuming that the device is resting on a piece of cloth, represented by line 16, of a mesh which will support stylus 37, which has been selected of the proper size therefor, it will be held as in Figure 3, line 16 representing the cloth. However, should a light bar occur by the failure of the loom as shown at 81, Figure 1, the stylus will drop through, followed by head 34, resulting in the position shown in Figure 2. It will be seen that, in the fall, 55 plunger 40 has come in contact with the cloth and was lifted, carrying with it pin 42, thereby releasing link 48. In turn, lever 53 was allowed to swing to the angle shown in Figure 10, paying off thread or wire 69 thereby allowing drop-wire 60 72 to fall and engage oscillating bar 67 over which it hung as shown in Figure 6. This will, for reasons already explained, operate to stop the loom. If desired a signal may be operated in connection with the detector.

After detection of the flaw and its remedy, the detector may again be placed in working form by the simple manual reengagement of link 48 with pin 42, which will obviously lift drop-wire 72 and relieve the knock-off mechanism of 5 the loom.

The head may be arranged in sections or otherwise so that it may be made heavier or lighter as would be governed by the density of the material being woven and, further, the stylus will 10 have a tip of a form best adapted to detect the flaw, its form varying with the shape of the opening in the mesh.

While I have described my invention strictly in accordance with the embodiment shown, it 15 must be understood that changes may be made in the construction of the device in order to suit various looms and to adapt the detector to varying conditions in the trade, without departing from the spirit of my invention and scope of my 20 claims.

What I claim is:

1. A light bar detector for looms having knock-off mechanism, comprising a support mounted on 25 said loom, a beam hinged at one end of said support to permit vertical motion thereof, a head at the other end of said beam, a stylus on said head resting on the fabric on said loom, a lever fulcrumed on said support, a link extending from 30 said head to one end of said lever, means in said head to normally engage said link, means in connection with the other end of said lever connecting with said knock-off mechanism, said engaging means adapted to release said link when coming in contact with said fabric. 35

2. In combination with a fabric producing loom, having knock-off mechanism; a support on said loom, a pivot on said support, an arm mounted at one end on said pivot and resiliently held in one position with reference thereto, a beam pivoted 40 at one end to the other end of said arm, means to resiliently hold said beam over the fabric substantially at right angle thereto, a head at the other end of said beam, a stylus on said head to support the same on said fabric, a plunger in 45 said head over said fabric, said plunger adapted to be raised by contact with the fabric in said head when said stylus falls in a light bar in said fabric, and means cooperating with the knock-off mechanism whereby the raising of said plunger will 50 actuate the same.

3. In combination with a fabric producing loom having knock-off mechanism; a beam supported on said loom at one end, a head at the other end of said beam having a stylus to support the same 55 on the fabric, a plunger positioned in a bore in said head, a downward pin dependent on said plunger, a link normally in engagement with said pin connecting with said knock-off mechanism, said head adapted to drop when its stylus meets a defect in said fabric thereby raising said plunger by contact with the fabric and releasing said knock-off mechanism. 60

JOHN DESROSIERS.
